GRINDING MACHINE GUIDE BLOCK

Joseph Sunnen, Kirkwood, Mo.

Application May 7, 1934, Serial No. 724,232

9 Claims. (Cl. 51—184.1)

My invention has relation to improvements in cylinder grinding machines and it consists in the novel features of construction more fully set forth in the specification and pointed out in the 5 claims.

The present invention is directed more particularly to the guide elements of a grinding machine of the type shown in my co-pending application, Serial No. 233,788, filed November 17, 10 1927, and is an improvement over the guide blocks forming the subject-matter of my Patent No. 1,929,613, dated October 10, 1933.

It is the object of the present invention to associate with the guide block a wiping element 15 which rubs over the cylinder wall when the grinding machine is in use and removes loose particles therefrom that have been removed by the abrasive element in the grinding operation.

It has been found in practice that when the 20 grinding elements or abrasive stones are of fine texture for the finishing grinding operation their abrasive property is reduced and may even be entirely overcome by the accumulation on or "loading" of the stone with fine iron particles 25 or iron dust that has been abraded from the cylinder wall. Of course the damage to the abrasive elements can be minimized if the grinding operation is discontinued at frequent intervals and the cylinder wall brushed or wiped to 30 rid it of the dust adhering to it. However, this is a laborious operation and very greatly increases the time required for the grinding of a cylinder. I have overcome the disadvantage of 35 the dust accumulation on the wall of the cylinder by combining with the guide element a suitable wiper which continually functions throughout the grinding operation and removes the fine iron particles from the cylinder wall as rapidly as they are deposited thereon.

40 The advantages of my improved guide element and its function as a wiper will be better apparent from a detailed description thereof in connection with the accompanying drawing, in which:

45 Figure 1 is a side elevation of a grinding machine provided with my improved guide elements, parts of said machine being broken away; Fig. 2 is a horizontal cross-section through the machine taken on the line 2—2 of Fig. 1; Fig. 3 is 50 an elevation of one of the guide elements looking at the working face thereof, part of the wiper associated therewith being broken away; Fig. 4 is a longitudinal section through the guide element 55 taken on the line 4—4 of Fig. 3; and Fig. 5

is an enlarged cross-sectional detail taken on the line 5—5 of Fig. 3.

Referring to the drawing, 1 represents the tool holder of a Sunnen cylinder grinder of the type described in the above referred to patent application, said holder being suspended by a yoke 2 and collar 3 from a drive shaft 4. The collar 3 is pivotally connected to the holder 1 by means of studs 5, 5, and the yoke 2 is pivotally connected to the collar by means of studs 6, 6 so 10 that a universal joint connection is formed between the shaft 4 and the holder 1. The holder 1 is provided with a longitudinally disposed axial bore 7 within which is housed a pinion shaft 8 rotatable by means of the adjusting head 9 for the purpose 15 of extending and retracting abrasive elements 10, 10 and guide elements 11, 11 comprising the tools carried by the holder. The construction and the operation of the tool holder, comprising the parts just described, is substantially the same 20 as that of the holder of my honing device described in detail in the aforesaid patent application and will not be further described herein except insofar as necessary to explain the operation of the guide elements 11, 11. 25

The guide elements 11, 11 comprise an angle-shaped block 12 carried on the outer ends of rack bar 13 which form the support for the block, said racks being slidably mounted in transverse bores 14, 14 intersecting with the axial bore 7 so that 30 the teeth *t* of the racks will mesh with the elongated pinion 8. The outer end of each rack bar 13 terminates in successively reduced portions 15 and 16, the reduced portion 15 passing through an opening 17 in what may be termed the base 35 18 of the guide block, while the reduced portion 16 passes through an opening 19 in a retaining strip 20, over which the extremity of said reduced portion 16 is riveted. Thus the retaining strip 20 is firmly fixed to the rack bar 13 in spaced 40 relation with the shoulder *s* formed by the reduced portion or stem 15. It will be observed that the length of the stem 15 is greater than the thickness of the base portion 18 of the block so 45 that space is provided between the inner surface 18' of the block and the shoulder *s* for a spring 21 in the shape of a concavo-convex washer or perforated disk. The spring washers 21 exert their influence to hold the block 12 outwardly in contact with the retaining strip 20 and possess 50 sufficient tension to hold the working surface 22 of the guide block firmly against the cylinder wall C when the grinding machine is in operation.

55 In operation the block 12 makes a yielding contact with the cylinder wall under the vibrations

of the machines in the manner as does the guide block of my Patent No. 1,929,613 aforesaid. Since the construction which permits of such yielding contact forms no part of the present invention 5 no further reference will be made thereto.

Novel features of the present invention are the thin corrugated cylinder contacting element 23 and the felt strip 24 which is cemented to the inner surface 25 of said element 23 by a layer of 10 a suitable adhesive or cement 26.

The angular block 12, and of course the cylinder contacting element 23, is composed of a material that is relatively non-abrasive as it must not score the cylinder wall during its movement 15 moreover, and it should also be comparatively friable so that when the pressure of the block against the cylinder wall C becomes greater than normal it will readily wear off. I have found that one material possessing these properties is 20 die cast metal containing approximately 94% zinc, 2% copper and 4% aluminum. The percentages are not critical and may be varied without materially affecting the properties of the resulting alloy. In performing grinding operations 25 in which abrasive stones of close texture are used it is also desirable that the extent of the working face 22 of the cylinder contacting element 23 be reduced to a minimum. It is for this reason that 30 said element is thin when compared with the cylinder contacting element of the guide block shown in my Patent No. 1,929,613. Reducing the thickness of the element 23 obviously reduces its ability to withstand pressure, so I have compensated therefor by forming the element 23 in the corrugated or zig-zag shape shown in Fig. 3. The corrugated shape of the element 23 provides comparatively wide bearing support against the cylinder wall without unduly increasing the friction thereof when the grinding machine is in operation. The corrugating of the element 23 provides 40 pockets 27, 27, etc., in which comparatively heavy applications of cement may be made to insure a secure fastening of the felt strip 24 to the element 23.

45 When the grinding machine is in operation the rotation is in the direction of the arrows (Figs. 2 and 5) so that the fine particles of iron deposited on the wall due to the abrasive action of either of the stones 10 will be picked up immediately by 50 the felt strip 24 of the guide block 12 following said stone, said particles becoming lodged in the felt strip 24 from which they may be removed at the conclusion of the grinding operation. Thus the felt strip 24 serves to keep the surface of the 55 cylinder comparatively clean and prevent the loading of the abrasive elements 10 with iron particles that ultimately destroy the effectiveness of the stone.

Having described my invention, I claim:

60 1. A guide element for cylinder grinding ma-

chines comprising a guide block adapted for contact with the cylinder, supporting elements for said block, and a wiper fixed to the block.

2. A guide element for cylinder grinding machines comprising an elongated block adapted for contact with the cylinder, supporting elements for said block, and an elongated wiper coextensive with and fixed to the block.

3. A guide element for cylinder grinding machines comprising a guide block having a base 10 component and a cylinder contacting component in angular relation, supporting elements for said block, and a wiper fixed to the block in the angle between said components.

4. A guide element for cylinder grinding machines comprising a guide block having a base 15 component and a cylinder contacting component in angular relation, supporting elements for said block, and a felt strip fixed to the block in the angle between said components.

5. A guide element for cylinder grinding machines comprising a guide block having a base component and a cylinder contacting component 20 in angular relation, supporting elements for said block, said cylinder contacting component 25 comprising a relatively thin, corrugated vane.

6. A guide element for cylinder grinding machines comprising a guide block having a base component and a cylinder contacting component 30 in angular relation, supporting elements for said block, said cylinder contacting component comprising a relatively thin, corrugated vane, and 35 a wiper of fibrous material disposed in the angle of said components and cemented to said corrugated vane.

7. A guide element for cylinder grinding machines comprising a guide block having a base component and a cylinder contacting component 40 in angular relation, supporting elements for said block, said cylinder contacting component comprising a relatively thin, corrugated vane composed of an alloy containing zinc, copper and aluminum.

8. A guide element for cylinder grinding machines comprising a guide block having a base 45 component and a cylinder contacting component in angular relation, supporting elements for said block, said cylinder contacting component comprising a relatively thin, corrugated vane composed of an alloy having a zinc base.

9. A guide element for cylinder grinding machines comprising a guide block having a base component and a cylinder contacting component 50 in angular relation, supporting elements for said block, said cylinder contacting component comprising a relatively thin, corrugated vane composed of an alloy containing zinc and aluminum.

JOSEPH SUNNEN.
